William Katz, INVENTOR.

BY

Geo. P. Kimmel ATTORNEY.

UNITED STATES PATENT OFFICE.

WILLIAM KATZ, OF ST. LOUIS, MISSOURI.

HAT.

Application filed June 2, 1925. Serial No. 34,395.

To all whom it may concern:

Be it known that I, WILLIAM KATZ, a citizen of the United States, residing at city of St. Louis, in the State of Missouri, 5 have invented certain new and useful Improvements in Hats, of which the following is a specification.

This invention relates to a hat of the straw type, and has for its object to provide, in a manner as hereinafter set forth, 10 a hat having interposed in its crown a plurality of perforated coils of braid forming continuations of the braid proper of the crown and which constitute a ventilating 15 means for cooling purposes, as well as permitting of the circulation of air through the crown of the hat above the head and further for reinforcing the crown of the hat.

A further object of the invention is to 20 provide, in a manner as hereinafter set forth, a ventilating straw hat, stiff or soft, whereby a free circulation of air over the head can be had when the hat is worn.

A further object of the invention is to 25 provide, in a manner as hereinafter set forth, a hat having in proximity to the bottom of the crown a ventilating element, and with the hat further provided with a sweat band 30 of a height with respect to said element to permit of a circulation of air through said element and over the top edge of the band, whereby the circulation of air over the top 35 of the band airs the head by a natural absorption of moisture, thereby producing a cooling effect upon the head of the wearer of the hat.

In the manufacture of straw hats, the braid is sewed spirally from the tip of the crown to the end of the brim, and in setting 40 up a hat, in accordance with this invention, a ventilating element is interposed in and connected to the braid forming the crown. The ventilating element consists of a specially constructed palmetto leaf braid which 45 is woven crosswise or two bars to form spaced openings between the bars and crosswise weave for permitting an easy flow of air through the crown of the hat. The ventilating element is inserted spirally as a 50 part of the crown itself, is secured to the braid of the crown and in no way weakens but on the contrary strengthens the crown of the hat, because palmetto braid is exceedingly tough and makes firm connection with the regular braid of the hat itself.

Further objects of the invention are to

provide, in a manner as hereinafter set forth, a ventilated straw hat, of the stiff or soft type, which is simple in its construction, strong, durable, thoroughly efficient 60 when worn, and comparatively inexpensive to manufacture.

With the foregoing and other objects in view, the invention consists of the novel construction, combination and arrangement 65 of parts, as hereinafter more specifically described and illustrated in the accompanying drawings, wherein is shown an embodiment of the invention, but it is to be understood that changes, variations and modifications 70 can be resorted to which come within the scope of the claims hereunto appended.

In the drawings wherein like reference characters denote corresponding parts throughout the several views:-

Figure 1 is a fragmentary view, in perspective, of a straw hat of the stiff type, in accordance with this invention.

Figure 2 is a fragmentary view, in elevation, of the ventilating element.

Figure 3 is a section on line 3—3, Figure 1.

Figure 4 is a vertical sectional view of a straw hat of the soft type, in accordance with this invention.

Figure 5 is a fragmentary view, in vertical section, of the crown of the hat shown in Figure 4.

Referring to Figures 1 and 2 of the drawings, a ventilated straw hat, in accordance with this invention, is illustrated of the 80 stiff type, and comprises a crown formed of an upper section 1, a lower section 2, an intermediate section 3, and a top 4. Projecting outwardly from the lower end of the lower section 2 is a brim 5. Surrounding the crown 1 and concealing the intermediate section 3 is a band 6, and secured to the inner face of the section 2, at the bottom thereof, as at 7, is a sweat band 8 of a height to terminate below the center of the section 3.

The top of the section 3 is secured, as at 9, to the inner face of the section 1, at the lower end thereof, and the bottom of the section 3 is secured, as at 10, to the outer face of the section 2, at the top thereof. The section 3 couples the section 1 to the section 2 and further maintains said sections 1 and 2 in spaced relation. The section 3 is formed of braid of a tougher type than the braid from which the sections 1 and 2 are constructed. The section 3 consists of

a plurality of spirals of braid and with the spirals secured together and to the sections 1 and 2. The section 3 has each of its spirals provided throughout with spaced 5 ventilating openings 11. The section 3 is termed a ventilating element and is formed from a specially constructed palmetto leaf braid that is woven crosswise on two bars 12, 13, see Figure 2. The crosswise weave is indicated at 14. The crosswise weave is set up with respect to the two bars to provide openings between said bars and the crosswise weave throughout the length of the braid and said openings permit an easy flow 15 of air through the crown. The braid, which forms the ventilating element, is inserted spirally and forms a part of the crown of the hat itself. The braid which forms the ventilating element in no way weakens but 20 on the contrary strengthens the hat, for palmetto braid is exceedingly tough and makes a firm connection with the regular straw braid of the hat itself. The braid, which forms the ventilating element, when 25 wound spirally, is set up whereby the spirals will overlap each other, as indicated at A, Figure 2 and with the spirals connected together by a row of stitching, indicated at B in Figure 2. When the spirals are overlapped, the lower bar of one spiral is positioned against the upper bar of an adjacent spiral.

The palmetto leaf braid, which forms the 30 ventilating element, can be had in any width to match the braid of the hat and can be sewed in as many spirals as desired to provide one, two, three or four rows of ventilating openings, as the greater number of rows, the greater number of ventilating 35 spaces for the crown. The ventilating openings formed in the palmetto braid are indicated at C, Figure 2, and are polygonal in contour.

The sections 1 and 2 are formed of closely 40 woven straw braid, reed fiber or paper.

The sweat band used in connection with the hat is narrow to the extent that when the band is secured to the lower section of the crown the circulation of air takes place 45 over the top edge of the band. The air circulating over the top edge of the band airs the head by a natural absorption of moisture, thereby producing a cooling effect upon the head of the wearer of the hat.

The band 6 is of the ordinary construction, and as such bands are usually woven in rib form and never very tightly woven, there are always a great number of small 50 openings that will permit free circulation of air when the band 6 surrounds the crown and conceals the ventilating element.

As before stated, the braid which forms the ventilating element is woven on two horizontal bars of palmetto leaf, the center 55 pieces being woven crosswise to form

natural, strong and unobstructed openings in the braid. This braid is joined to and made a part of the crown of the hat by sewing along the horizontal bars of the braid, and, therefore, it is conveniently secured in 60 position to form not only a ventilating element, but also a strengthening element for the crown.

With reference to Figures 4 and 5, the hat is of the Panama or soft type and includes 65 a crown formed of an upper section 15, a lower section 16 and an intermediate section 17. Projecting outwardly from the lower end of the lower section 16 is the brim 18. Secured to the inner face of the section 16, 70 at the lower end thereof, as at 19, is a sweat band 20, which projects slightly above the section 16 and has its top edge terminate between the center of the section 17. Surrounding the sections 15 and 16, as well as 75 concealing the section 17, is a hat band 21.

The section 17 provides the ventilating element and is constructed in the same manner as that referred to in connection with section 3 of the hat structure shown in Figure 1. The bottom of the section 15 is in-turned upwardly against itself, as at 22, and the top of the section 16 is in-turned downwardly upon itself as at 23. The in-turned portions 22 and 23 abut against the inner 80 face of the sections 15 and 16 respectively. The top of the section 17, which forms the ventilating element, is secured against the in-turned portion 23 by a row of stitching 24, and the bottom of the section 17, which forms the ventilating element, is secured against the in-turned portion 23 by a row 85 of stitching 25.

The form of hat shown in Figure 4 functions in the same manner as the form of hat 90 shown in Figure 1.

It is thought that the many advantages of a ventilated straw hat, in accordance with this invention, can be readily understood, and although the preferred embodiments of the invention are as illustrated and described, yet it is to be understood that changes in the details of construction can be had which will fall within the scope of the 95 invention as claimed.

What I claim is:—

In a hat, a crown formed of an upper section, a lower section and an intermediate section consisting of a braid interposed between and secured to said sections and formed of two spaced horizontal bars of vegetable material and a pair of spaced strands of vegetable material, each of said strands at spaced points of its length bent around said bars, the bent portions of each strand at one bar arranged out of alignment with the bent portions of the strand at the other bar whereby the portions of each strand between the bars will extend alternately in opposite directions at an inclina- 100

tion, the inclined portions of one strand crossing the inclined portions of the other strand centrally thereof to provide in connection with the bars spaced uniform openings throughout the braid and each extending from one bar to the other, said intermediate section formed of material of

greater strength than the material of the other of the sections for maintaining these latter in spaced relation and for strengthening the crown. 10

In testimony whereof, I affix my signature hereto.

WILLIAM KATZ.
